LOCK FOR THE RELEASE OF EROSION FLUIDS UNDER PRESSURE

Kurt Bredtschneider, Dortmund, Germany

Application September 1, 1934, Serial No. 742,468
In Germany July 4, 1933

4 Claims. (Cl. 137—152.5)

My invention relates to a lock for the release of erosive fluids under pressure. An erosive fluid may be a liquid, a gas, or a mixture of liquids and/or gases, in which erosive matter is suspended. Such erosive fluids are present, for instance, in high-pressure reaction systems for the hydrogenation of carbonaceous materials with nascent hydrogen, in high-pressure reservoirs of other kinds in oil wells, etc. The release of 10 liquids or gases under high pressure, for instance the reduction of the high pressure in a reaction system of the kind described from high to lower pressure presents a difficult problem if the fluid is erosive, as the closing and throttling means are rapidly worn to destruction by the erosion of the 15 solid substances which are suspended in the fluid, and also by chemical corrosion.

In cases of this kind it has already been suggested to use exchangeable throttling means such as nozzles or perforated disks of particularly hard material. Such means, however, require frequent exchanging notwithstanding their hardness, since the free sectional area soon becomes too large under the wear of the erosive matter in the fluid, and the desired throttling action is not accomplished. As such nozzles etc. are made of high-class materials, the first cost as well as the cost of maintenance are very high.

It is an object of my invention to provide a 30 lock of the kind described, whose throttling means do not require frequent exchanging. To this end I provide a casing which may be connected to a high-pressure reservoir, for instance to the reaction chamber referred to. In this casing, I arrange a tubular member for discharging the fluid from the casing, a valve whose outside diameter is substantially equal to the inside diameter of the tubular member, and means for shifting the valve with respect to the tubular member.

Under normal conditions the end of the valve is adjusted at some distance from the bore in the tubular member so as to throttle the free sectional area for the discharge of the fluid from the casing, as required for reducing the pressure in the 40 casing down to atmosphere or to any other lower pressure. As the end of the valve wears off, its outside diameter decreases, while at the same time the inside diameter of the tubular member increases, and the throttling action is deteriorated. This is made up for by moving the worn portion of the valve into the worn portion of the tubular member until the initial throttling action has been reestablished by the cooperation of the 45 less worn, or unworn, portions of the valve and member. In this manner the life of the lock is

greatly prolonged, as the valve and the tubular member require exchanging only after they have become completely worn. The valve and the tubular member may be made of a material of equal hardness, or of materials having different 5 hardness, so that the softer part wears at a faster rate.

In the drawings affixed to this specification and forming part thereof devices embodying my invention are illustrated diagrammatically in axial 10 section by way of example.

In the drawings

Fig. 1 shows a lock with a threaded spindle and an exchangeable valve on the spindle,

Fig. 2 shows the condition of this lock when the 15 valve and the tubular member are worn down to some extent,

Fig. 3 shows means for rotating the valve through a spur gear and pinion, in order to prevent unequal wear thereof,

Fig. 4 shows a lock in which the valve is placed on an impeller and rotated by the flow of the liquid through the casing,

Fig. 5 shows a lock in which the valve is adjusted automatically under the influence of the 25 pressure in a pipe connecting the casing to a supply of fluid under pressure,

Fig. 6 shows a lock in which the valve is adjusted automatically under the influence of the 30 outflowing fluid, and

Fig. 7 shows a lock in which the valve is adjusted automatically by the pressure gradient at opposite sides of a choke disk in the outflow pipe of the casing.

Referring now to the drawings, and first to 35 Figs. 1 and 2, the casing 1 of the lock is equipped with an inlet pipe 2 for connecting it to a supply of liquid or gas under pressure (not shown). 3 is a tubular member which is inserted in the open lower end of the casing 1 and is provided with a 40 shoulder 4 bearing on the lower end of the casing; 5 is a flange which is held against the lower end of the shoulder 4 by screws 6, and 7 is an outlet pipe on the flange 5. The upper end of the casing 1 has a central bore in which is inserted a 45 spindle 8 with a detachable valve 9 at its lower end. The spindle 8 and the valve 9 are connected by a threaded pin 10 on the lower end of the spindle or may be connected by other suitable means. The outside diameter of the valve 9 is 50 equal, or substantially equal, to the inside diameter or bore of the tubular member 3.

Suitable means such as a stuffing box 12 are arranged on the casing 1 at its upper end for preventing leakage of the liquid or gas along the 55

spindle 8. The upper end of the spindle 8 is threaded at 13 and engages in the thread of a nut 14 which is spaced from the upper end of casing 1 by screws 15. 16 is a handwheel for turning the spindle 8 in the nut 14.

The free sectional area available for the outflow of the liquid or gas from the casing 1 is varied by turning the spindle 8 so as to move the lower end of the valve 9 toward, or away from, the upper end of the bore in the tubular member 3. The outflowing liquid or gas is throttled to a greater or lesser extent in the manner described until the lower end of the valve 9 enters the bore of the tubular member 3, whereupon the outflow 15 is stopped or reduced to a minimum, as the outside diameter of the valve is substantially equal to the inside diameter of the bore in the tubular member 3.

The erosion of the tubular member 3 and of the valve 9 by the liquid causes a gradual widening of the bore, as shown at 3a in Fig. 2, and a gradual reduction of the outside diameter of the valve 9, as shown at 9a, but the lock can still be operated until the tubular member 3, or the valve, or both, has become worn throughout its length. That part which has become worn so as to render it inoperative, is exchanged.

The valve 9 turns as the spindle 8 is turned by its hand wheel 16 but this turning is only slight 30 and ceases when the valve is in one of its final positions, and so the valve may be fluted locally by erosion. Such local wear is prevented by rotating the valve, as will now be described.

Referring now to Fig. 3, the valve spindle 8 is provided and arranged as described with reference to Fig. 1, but it is not threaded at its upper 35 end and the handwheel 16 and the nut 14 are dispensed with. Instead, a threaded spindle 17 is inserted in a threaded bore of a bracket 18 which may be cast integral with the casing 1, and a hand wheel 19 is secured on the lower end of the spindle. The upper end of the spindle is free to turn in a yoke 20 which is attached to the upper end of spindle 8. Splined on the spindle 8 at 21 is a spur gear 22 with which meshes a pinion 23 on a shaft 24.

When the shaft 24 is rotated by any suitable means (not shown) the spur gear 22 is rotated at a slower rate and the spindle 8 on which it is 50 splined, is turned at the same rate. Obviously, means (not shown) must be provided for holding the spur gear 22 and the pinion 23 against axial displacement while the spindle 8 is shifted. By the rotation of the valve 9, unequal wear of the valve by erosion is prevented.

The flow of the liquid or gas may be utilized for rotating the valve 9, as will now be described with reference to Fig. 4. The spindle 8 is threaded at 13 and engages in the nut 14, as described with reference to Figs. 1 and 2, but the lower end 60 of the spindle is equipped with a collar 25 on which is seated the boss of an impeller 26. 27 is an antifriction bearing between the collar and the boss, and 28 is a stuffing box on the impeller for preventing access of liquid or gas to the antifriction bearing 27. 29 are vanes on the impeller which are in line with the opening of inlet pipe 2 into the casing so that the liquid or gas flowing from 2 toward 3, rotates the impeller. The valves 9 is secured to the impeller and partakes in its 70 rotation.

Under certain conditions, and particularly if it is desirable to keep up a definite pressure in the reaction vessel or the like to which the casing 1 is connected by pipe 2, without relying on the atten-

tion and care of an operator, automatic means may be provided for regulating the free sectional area for the liquid or gas, and such means will now be described with reference to Figs. 5, 6, and 7; in these figures the spindle is shown as integral with the valve, i. e., only the spindle 8 is provided and its lower end replaces the separate valve 9. It is understood, however, that a separate valve and spindle may be provided, and that the valve may be rotatable, as described with reference to 10 Figs. 3 and 4. The yoke 20 is attached to the upper end of spindle 8, as described, but the threaded spindle 17 which engages the other end of the yoke, Fig. 3, is replaced by the rod 30 of a piston 31 in a cylinder 32.

Referring now to Fig. 5, the lower end of the cylinder 32 is connected to the inflow pipe 2 so that the pressure in the pipe acts on the lower face of the piston 31. A bracket 33 is secured to the upper end of cylinder 32 and a spring 34 is placed about the piston rod 30 and bears on a disk 35 on the rod 30 with its lower end while its upper end is supported by the upper end of bracket 33. It will be understood that the movement of the spindle 8 with respect to the bore of 25 the tubular member 3 is a function of the pressure in the inlet pipe 2 and of the pressure of the spring 34.

In the examples illustrated in Figs. 6 and 7, the cylinder 32 is closed at both ends and connected to the casing 1 by a bracket 36. Obviously, the cylinder 32, the casing 1, and the bracket 36 might be cast as a single unit. 37 is a pipe which is connected to the space above, and 38 is a pipe which is connected to the space below, the piston 35 31. The two pipes are connected to the upper and lower ends of a relay in a casing 39. The relay may be electrical, mechanical, hydraulic, or pneumatic, and, in the example illustrated in Fig. 6, is connected to the discharge pipe 7 by a 40 pipe 40.

Referring to Fig. 7, the arrangement is similar to the one described with reference to Fig. 6 but a choke disk 41 is inserted in the discharge pipe 7, and the spaces upstream and downstream of 45 the disk are connected to the relay 39 by pipes 42 and 43, respectively.

The relay 39, as mentioned, may be of any suitable kind. For instance, the pressure from pipe 40, Fig. 6, or the differential pressures from pipes 42 and 43, Fig. 7, may control a piston such as 31 which, through suitable valves, regulates the admission of liquid or gas to the pipes 37 and 38, or the relay may be equipped with electrical or other means for regulating the pipes 37 and 38. 55 I am not limited to the operation of the spindle 8, with or without the detachable valve 9, through mechanical means, such as the spindle 17 in Fig. 3, or through pneumatic or hydraulic means, such as the piston 31, Figs. 5, 6, and 7, but the spindle 60 may be reciprocated, with or without being rotated, by electrical or magnetic means. Thus, the piston rod 30 may be reciprocated by an electromagnet or a solenoid, or by an electric motor through suitable reduction gearing. It is understood that I am not limited to any particular means for rotating the spindle 8 or its valve 9, and for reciprocating the spindle or the valve, as the case may be.

In the initial position of a valve 9 or a spindle 8 70 whose lower end acts as the valve, and which is not worn, as shown for the valve 9 in Fig. 1, the lower end of the valve is clear of the bore in the tubular member 3. The fluid whose pressure is to be relieved, and which is admitted to the cas- 75

ing through pipe 2 from, say, a reaction chamber of the kind referred to, (not shown), is throttled to a greater or lesser extent by adjusting the spindle 8 so that the end of the valve 9 moves 5 nearer to, or further away from, the upper end of the tubular member 3. When the valve and the tubular member wear at 9a and 3a, respectively, as shown in Fig. 2, the valve is lowered into the tubular member until the desired throttling 10 action has been reestablished, and this is repeated until the parts have become worn throughout.

By the means illustrated in Figs. 3 and 4, the valve is rotated permanently and not only while it is adjusted, as in Figs. 1 and 2. The valve is 15 rotated during its operation while above, or within, the tubular member 3. Any other means than those illustrated in Figs. 3 and 4 may be used for rotating the valve 9, or the spindle 8.

In the lock illustrated in Fig. 5, the valve is 20 regulated under the influence of the pressure ahead of the tubular member 3. This may be effected by other means than those illustrated in Fig. 5, for instance by means operated by viscous liquid (oil), or by a relay as shown for another 25 kind of lock in Figs. 6 and 7.

In these figures, the valve is regulated automatically by the pressure at the rear of the tubular member 3. In both cases, it is also possible to regulate the valve automatically by the 30 quantities of fluid supplied to, or discharged from, the casing 1. This may be effected by any suitable means, such as the relays 39. The lock illustrated in Fig. 6 is particularly suitable for 35 regulating the valve in conformity with the pressures, while the lock illustrated in Fig. 7 is suitable for regulation by quantities.

The automatic means described make up for the wear of the valve and the tubular member, and always produce the required throttling action.

40 The fluid may also flow in opposite direction, from pipe 7 to pipe 2, without departing from my invention, and the operation is similar to the one described.

I wish it to be understood that I do not desire 45 to be limited to the exact details of construction shown and described for obvious modifications will occur to a person skilled in the art.

I claim:—

1. In a valve for erosive fluids under high pres-

sure in combination, a valve casing formed with an inflow and an outflow port, a sleeve-shaped lining with a cylindrical bore forming the valve seat extending into one of said ports and held therein for ready exchange, a cylindrical rod forming the valve body in line with and fitting into the bore of said sleeve and means, to which said rod is fitted for ready exchange, for axially adjusting said valve body towards and away from the bore in said sleeve. 10

2. In a valve for erosive fluids under high pressure in combination, a valve casing formed with an inflow and an outflow port, a sleeve-shaped lining with a cylindrical bore forming the valve seat extending into one of said ports and held therein for ready exchange, a cylindrical rod forming the valve body in line with and fitting into the bore of said sleeve, and means, to which said rod is fitted for ready exchange, for axially adjusting said valve body towards and away from the bore in said sleeve, and arranged to be operated by the fluid traversing the valve. 15

3. In a valve for erosive fluids under high pressure in combination, a valve casing formed with an inflow and an outflow port, a sleeve with a 25 cylindrical bore extending into one of said ports and held therein for ready exchange, a cylindrical valve body in said casing in line with and fitting into the bore of said sleeve and means comprising an impeller, to which said valve body 30 is fitted for ready exchange, for axially adjusting said valve body towards and away from the bore in said sleeve.

4. In a valve for erosive fluids under high pressure in combination, a valve casing formed with 35 an inflow and an outflow port, a sleeve-shaped lining with a cylindrical bore forming the valve seat extending into one of said ports and held therein for ready exchange, a cylindrical rod forming the valve body in line with and fitting into the bore of said sleeve, and means comprising a piston, to which said rod is fitted for ready exchange, a cylinder surrounding said piston and liquid connections between the inflow side of said casing and said cylinder on either side 40 of said piston, for axially adjusting said valve body towards and away from the bore in said sleeve. 45

KURT BREDTSCHEIDER.
